UNITED STATES PATENT OFFICE

LESTER C. LICHTY AND MICHAEL PERUGINO, OF NEW HAVEN, CONNECTICUT

FINGER GUARD

Application filed May 1, 1928. Serial No. 274,234.

One object of the invention is to provide a finger guard to prevent the sucking of thumbs and fingers by infants and small children.

5 Another object of the invention is to provide such a finger guard which is constructed of a single piece of wire.

Another object of the invention is to provide such a finger guard which is formed of 10 a single piece of spirally wound wire.

Another object is to provide a finger guard which is constructed at small cost, durable in construction and easy to market.

Another object is to construct a wire finger guard which is safer than guards of this 15 type heretofore constructed.

Other objects will appear hereinafter.

Referring to the drawings:

Figure 1 is a plan view of a finger guard 20 embodying our improvements showing the same applied to a child's or infant's thumb.

Figure 2 is an end elevation of a construction embodying our improvements showing the form upon which it is wound in dotted 25 lines.

Figure 3 is a side elevation of the finger guard shown by Figure 2.

A finger or thumb guard to prevent sucking of fingers or thumbs by small children has 30 heretofore proven very helpful to break this habit of small children. Such a finger guard constructed of wire has cheapened the manufacture of such guards but it has been necessary heretofore to construct each of such 35 guards of more than a single piece of wire. Guards made of a number of pieces of wire are usually so constructed that when any joint becomes broken the end of a wire is loose and the child is apt to endanger an eye 40 or other part of the body. No matter what joint breaks in our device there are no sharp prongs to develop. Also, the breaking of one or a number of joints does not render the article useless.

45 After a number of experiments extending

over a considerable period of time, we have discovered a method of making a finger guard constructed of a single piece of wire.

Upon a suitable mandrel (indicated by dotted lines in Figure 2) the wire is wound spirally upward beginning at 12 until the top of the form is reached, whereupon a loop 7 is made over the top of the mandrel and the downward spiral winding begins. At the bottom a loop 2 is made having sides 6 and 50 3 and a second upward spiral is begun. The winding continues until the top is reached and a second top loop 4 is made and the wire is wound spirally downward and is fastened to 3 by bent portion 5. The other end is 55 similarly fastened at 8 to portion 6. The winding is preferably done as stated above and follows the arrows in Figure 2. At the beginning of the winding the end 8 may be held by being forced in a hole in the mandrel. 60 To fasten end 5, portion 3 is raised to allow the end of the wire to pass under it, or a slot 65 may be cut in the mandrel to allow the wire to pass under 3. The wire is then turned over 3 to form fastening 5. 70

In another manner of practicing our method, we first take a single strand of wire and make a loop 2. Upon a suitably shaped mandrel or form one end of this loop is wound spirally beginning at 3 until the top of the 75 form is reached. Around the top of the form a second loop 4 is formed and the wire is now wound spirally downward until the wire comes in contact with the part 3 whereupon it is made fast to this portion by turning the 80 wire around said portion as indicated at 5. The other side of the loop 2 designated 6 is now wound spirally upward on the form until the top portion of the same is reached, whereupon a third looped portion 7 is made 85 and the wire is now wound spirally downward and attached to the upper portion of said portion 6 at 8.

In making the second upward spiral starting from portion 6 the wire is preferably 90

crossed alternately under and over the upward and downward spirals formed during the first winding operation, although we wish to be expressly understood as not limiting ourselves to such a construction.

5 In making our finger guard we may construct the same by hand operations or may employ a machine to perform the winding operations including forming the loops, spirals and fastening the ends (such fastenings being indicated at 5 and 8). However we may use a machine to perform one or more of the above operations, performing those not made by machine, by hand labor.

10 15 As still another method of constructing our finger guard, the winding operations can be started simultaneously beginning at the side portions 3 and 6 of the loop 2, winding the spirals upwardly at the same time, constructing the loops simultaneously and then downwardly and finally connecting the ends 5 and 8. This method may be employed with especial advantage when the guard is constructed by a machine. The machine may 20 25 perform the final operation of turning the ends 5 and 8 or this operation could be made by hand.

30 In another method of constructing our guard, the upward spiral on one side is first made and while the downward spiral is being made the second upward spiral is made, followed by the second downward spiral.

35 In still another method the downward spirals are made first either in succession or simultaneously followed by the upward spirals, either in succession or simultaneously.

40 We prefer, however, to use the method first set forth in this specification, although we do not wish to be limited to such method.

45 After having formed the guard the preferable portions of the wire which cross each other and portions 5 and 8 are brazed, welded or are soldered together as indicated at 9 and 10 or the joints may be soldered by dipping the guard and mandrel in molten solder after which the guard is removed from the mandrel.

50 In order to prevent removal of the guard by its wearer a piece of tape or string 11 may be attached to the loop 2 and fastened around the wearer's wrist.

We claim:

55 1. A finger guard consisting of a plurality of oppositely wound spirals formed from a single piece of wire, the wires of said spirals crossing each other at a plurality of points.

60 2. A finger guard to prevent the sucking of fingers by children consisting of a single piece of wire, said wire having a plurality of crossed spiral convolutions and means for looping the ends of the wire to certain of said convolutions.

65 3. A thumb-sucking preventer, formed from a single piece of wire doubled at the

center, the ends wound spirally in opposite directions to the tip, where they are looped backward and wound spirally in reverse directions, crossing and united to the spirals first formed, providing a cage-like structure adapted to set over a thumb or finger and cover the first joint.

70 In testimony whereof we have hereunto set our hands this 28th day of April, A. D. 1928.
